SADDLE FOR SUPPORTING A SPRINKLER HEAD

Floyd A. Terwilliger, 1232 SE. 12th Ave.,
Deerfield Beach, Fla.

Filed Jan. 6, 1965, Ser. No. 83,297

Term of patent 14 years

(Cl. D91—3)

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.

FIG. 1 is an elevational view of one side of a saddle for supporting a sprinkler head made according to one embodiment of this invention;

FIG. 2 is an elevational view of one end thereof;

FIG. 3 is an elevational view of the other side thereof;

FIG. 4 is a plan view thereof;

FIG. 5 is a bottom view thereof;

FIG. 6 is a sectional view on the line 6--6 of FIG. 1 looking in the direction of the arrows;

FIG. 7 is an elevational view of one side of a modification of the saddle for supporting a sprinkler head;

FIG. 8 is an end elevational view thereof;

FIG. 9 is an elevational view of the other side thereof;

FIG. 10 is a plan view thereof;

FIG. 11 is a bottom view thereof; and

FIG. 12 is a sectional view on line 12--12 of FIG. 7 looking in the direction of the arrows.

In certain figures in the drawings part of the piping, to which the illustrated saddle is secured, is outlined by broken lines for illustrative purposes only.

I claim:

The ornamental design for a saddle for supporting a sprinkler head, as shown and described.
